UNITED STATES PATENT OFFICE

EMIL L. TRANAAS, OF MILWAUKEE, WISCONSIN, ASSIGNOR TO KOEHRING COMPANY,
OF MILWAUKEE, WISCONSIN, A CORPORATION

CONTROL MECHANISM FOR CONCRETE PAVING MACHINES

Application filed December 10, 1929. Serial No. 413,029.

The present invention comprises certain improvements in what are known as paving machines for the laying of concrete, which machines today are practically universally designed to embody a concrete mixer, a distributing attachment in the form of a boom and bucket to receive and distribute the concrete mixed by the mixer, a charging skip or device for elevating the combined aggregates to charge them into the mixer, and suitable time controlling means determining the discharge action of the machine.

The purpose of the invention is to carry forward by way of improvements and special controls intermediate the various parts of the machine, the inventions embodied in Robb Patents No. 1,370,497 of March 1st, 1921 and No. 1,660,301 of February 21st, 1928, and Webb Patent No. 1,628,378 of May 10th, 1927, the last patent including particularly a special automatic discharge control mechanism for improving that part of the machine embodied in Robb Patent No. 1,370,497, aforesaid.

Now in the operation of machines for paving purposes of the type referred to, certain interlocking or cooperative sequential operations of the various mixing, charging and discharging instrumentalities are desirable.

Again, the overlapping of the operating times of certain operations is necessary as is presented in the Robb Patent No. 1,660,301. Improved devices for obtaining these results are the subject matter of this invention, and additional devices for controlling the mechanisms so that they will not work in automatic succession, or with automatic overlapped actions, are now provided.

In carrying out this invention, the machine has been designed to afford what may be called a full automatic operation performing a full automatic cycle to the extent that the action of the upward movement of the skip, upon charging, starts what is known as the batchmeter time control into action and causes the subsequent proper timed operations of the discharging device of the mixing drum, and the later actuation of the skip or charging device control to raise the skip to its charging position and thus complete said

automatic cycle, the supplying of water to the mixing drum for mixing with the dry aggregates being taken care of by the skip operation, as has been previously proposed in the prior art patents herein referred to.

In the further carrying out of the invention, the full automatic cycle just above mentioned may be discontinued by operation of a manual controlled instrumentality to the extent of placing the skip raising movement for charging action under the control of the operator.

Likewise, the automatic cycle above outlined is susceptible of modification by a manual operator control of the discharge of the mixer which is a power driven type of discharge, an instrumentality being interposed so that if desired, a manual operation of the power discharge may be employed. However, provisions are made so that this manual control cannot be called upon or put into action at any time when the automatic cycle has been started to the extent of placing the control of the discharge under the action of the batchmeter timing device.

Another phase of the invention is involved in that portion of the control operation in which the power discharge chute mechanism is placed under manual control so that the discharge chute may under certain conditions be moved to discharging or non-discharging positions. When this control is established by the action of proper instrumentalities the operator has within his power to hook up the discharge action of the chute power discharge for the mixer with the automatic means for initiating the raising movement of the charging skip. He need not necessarily interlock these two actions because provisions are made so that the hook up may be effected or not effected.

A manual provision is made in the control mechanisms of the machine such that the automatic instrumentalities may be incapacitated to actually cause an operation of the power discharge to effect discharging of the mixer, in which event these instrumentalities will merely serve to unlock the power discharge to place it under the manual

control which has been suggested above as one of the features of the invention.

Specifically new instrumentalities are employed for causing the movement of the power discharge chute to non-discharging position, if it be previously in a discharging position, invariably effected under the action of the raising of the skip to charge the mixer, and these instrumentalities are likewise novel in their cooperative action to cause discharging movement of the discharge chute. In these instrumentalities are included means such that when the discharge chute is in non-discharging position, it will not be controlled or caused to move to a discharge position under any circumstances by the rising action of the skip. In other words, the purpose of the invention in this aspect is to maintain the discharge chute under absolute control to move to discharging position as a part of the function of the batchmeter timing control device, or under manual control when said chute is not controlled by the batchmeter. But never is it desired to permit the rising movement of the skip to effect a discharging action of the discharge chute.

This invention also involves certain other features of construction and operation in one way or another, related to the foregoing features, and which will appear more fully as this description proceeds.

For a full and more complete understanding of the invention, reference may had to the following description and accompanying drawings, in which—

Figure 1 is a side elevation of the concrete paving machine showing my invention applied thereto, a portion of the distributing boom and the skip being broken away and the skip shown in charging position in full lines and receiving position in dotted lines.

Figure 2 is a fragmentary enlarged elevation of the discharge end of the paver showing the connection between the power discharge unit and the discharge chute for the mixing drum.

Figure 3 is a vertical, sectional view through the power discharge casing, certain of the parts being broken away and shown in section, the release mechanism being shown in set position in full lines and released position in dotted lines.

Figure 4 is a sectional view taken approximately on line 4—4 of Figure 3, looking in the direction of the arrows.

Figure 5 is an end view of the power discharge, parts of the casing being broken away to show more clearly certain details of the internal mechanism.

Figure 6 is a diagrammatic sectional view through the upper portion of the power discharge casing, showing certain of the parts in the position which they occupy during the mixing cycle of the paver.

Figure 7 is a diagrammatic view similar to Figure 6, showing the batchmeter control release lever cammed out of operating position, showing the parts in mixing cycle position in full lines and showing the parts at the end of the mixing cycle when the batchmeter has tripped off in dotted lines.

Figure 8 is a diagrammatic plan view of the skip hoist lever push rod actuating mechanism.

Figure 9 is a horizontal sectional view showing the power discharge push rod for actuating the skip hoist lever and the shiftable pin for connecting the power discharge with the skip hoist lever.

Figure 10 is a diagrammatic perspective view of the skip hoist lever mounting and the skip actuated mechanism for the power discharge release lever.

Figure 11 is a vertical sectional view taken approximately on line 11—11 of Figure 9, showing the skip hoist lever retractable pin in engaging position in full lines and disengaged position in dotted lines.

Figure 12 is a view similar to Figure 11, showing a modified form of the invention wherein the skip hoist lever is normally disengaged with relation to the power discharge push rod assembly and must be manually engaged to cause automatic engagement of the skip hoist clutch, the dotted lines of the figure showing the manually actuated foot lever in depressed position;

Figure 13 is a somewhat diagrammatic showing of the operating parts of the power discharge as shown in Figure 3, disclosing the manual means for rendering the batchmeter ineffective to operate the power discharge, certain of the parts and the casing being omitted for the sake of clearness.

General features of machine

Like reference characters refer to like parts in the several figures of the drawings.

A represents the traction support on which is mounted the frame B. The skip C is pivoted at D to the frame and is adapted in one of its positions to receive aggregates to be mixed and elevated to discharge the aggregates into the mixing drum which is revolvably carried within the frame B. A boom F is pivotally supported by the frame B at the rear of the machine and carries the spreading bucket G which receives the aggregates after they have been mixed in the mixing drum E. A discharge chute H is pivotally supported by the frame B and is adapted to be swung into discharging position at the end of the mixing period by the power discharge mechanism I, forming a part of my invention.

A batchmeter J of the usual type is provided which controls the mixing period of the aggregates within the mixing drum. The frame B carries the engine housing K,

within which is located the power plant for supplying operating power to the machine. The shaft L, operated by the engine, carries the pinions M which mesh with the ring 5 gears on the mixing drum E and cause rotation of this drum. The shaft L provides a driving means for the mechanism within the power discharge casing I.

The batchmeter above mentioned may be 10 of the type disclosed in Winkler Patent No. 1,451,483 of April 10th, 1923.

Power discharge

The power discharge mechanism now to be 15 described may be of different types and the specific devices which connect the actual power instrumentalities with the discharge chute of the mixer form the basis of a separate application for patent and will, therefore, be 20 very generally referred to below. The power discharge mechanism itself, as hereinafter set forth however, forms a part of the present invention.

Referring to Figure 2 of the drawings, 25 it will be noted that a shaft 17 extends out of the power discharge case I and carries the crank N affixed thereto, to which crank is attached a link O at one end, the other end of the link being secured to a T-shaped 30 lever P. The lever P is secured to the link Q connected to the off-standing arm R of the discharge chute H. Reference is now made to Figures 1, 3, 5, 6 and 7 for an understanding of the mechanical parts within 35 the power discharge casing.

The internal mechanism just mentioned, in the casing I, is arranged to shift the crank N through an arc of 180 degrees and this action through the linkage O, P and Q causes 40 the discharge chute H to move either to non-discharging position as shown in Figure 2, or discharging position in which it inclines oppositely and permits the materials mixed in the drum E to flow out of the same into 45 the distributing bucket G.

Figures 3, 4, 13 and 5 perhaps show the parts within the casing I to best advantage. At the top of the casing I is mounted the batchmeter-operated lever 1, connected with 50 the batchmeter as will be later described and pivoted to be rocked on the casing I upwardly and downwardly, upwardly when the batchmeter is to release the mechanism to cause the discharge chute to assume a discharging position; downwardly, when the batchmeter is reset preliminary to a subsequent release action for causing the discharge of the mixer. The lever 1 is carried by a sleeve 2 shown in dotted lines in 55 Figure 5 and similarly in Figure 3 as loose upon the shaft 41. On the shaft 41 is carried the fixed arm 42 which pivotally supports near its upper end, the latch bar 3 having an abutment or shoulder 4 arranged 60 to engage and rock the bell crank release 65

lever 5. The lever 5 has its left arm equipped with a lock lug 6 movable into and out of engagement with a horizontal detent lever 7 pivoted in the casing. The detent lever 7 is adapted to engage at its free end, the upper end of the clutch engaging lever 8, and said clutch engaging lever is pivoted at its lower end at 8a in the casing, and is provided with an off-standing arm 8b normally acted upon by the upward expansive action of a spring 9.

Obviously, an interlocking of the detent lever 7 permits the upper end of the clutch engaging lever 8 to cam the detent lever upward incident to the movement of the lever 8 to the right under the expansive action of the spring 9. The lever 8 controls rollers 10, which, practically speaking, move with the lever and are supported by curved arms 8c which arms project from and are rigid with the detent 8b underneath which the spring 9 is seated. In effect, therefore, the rollers 10 and the lever 8 rock together, said rollers engaging the thrust disc 11 which is mounted slidably upon the shaft 14, said 90 thrust disc being cooperative with the discs 12 of a multiple disc clutch device to establish a driving relation between the driving sleeve 13 and the driven shaft 14 which supports said thrust disc. The driving sleeve 95 13 is designed to be constantly driven by any suitable connection with the driving shaft L which has previously been referred to and to this end the sleeve 13 has a driven clutch member 13a.

The shaft 14 has keyed thereon a pinion 15 which meshes with the pinion 16 fixedly carried by the hollow shaft 17. The crank N is secured to the outer end of the hollow shaft 17. Keyed to the inner end of the hollow shaft 17 is the pinion 18 which meshes with the pinion 19 secured to the thrust disc 11. The thrust disc 11 and the pinion 19 are fixed with respect to each other but are loosely carried by the shaft 14. The 110 thrust disc 11 has diametrically opposite depressions 20 arranged in alignment with the rollers 10 to permit the rollers to relieve the pressure on the multiple disc clutch when the lever 8 is latched to the left, as shown in full lines in Figure 3. A latch member 21 is pivotally carried by the casing and is adapted to drop into the diametrically opposite notches 22 between the flanged extensions 23 of the gear 16, see Figures 3 and 4. This latch member is adapted to hold the gear 16 and the crank N in mixing or discharging position. As the lever 8 is released by the rocking of the bell crank 5, and the spring 9 rocks this lever to the dotted line position in Figure 3, a push rod 24 above the arm 8b is actuated to lift the latch 21, permitting the gear 16 to rotate.

With the parts in the dotted line position, as shown in Figure 3, as the gear 15 rotates 130

the shaft 17, carrying the gear 16, this shaft drives the pinion 18 which in turn rotates the thrust disc 11 and pinion 19 and an inclined wall 19' leading from the base of depressions 20 in the disc 11, cams the lever 8 to the left, permitting the latch 21 to be lowered by gravity and the down pressing spring 21a whereupon it will ride on the flanged periphery of the pinion 16 until the next notch 21 10 is reached when the latch will drop into the opposite notch 22 and stop rotation of the chute operating shaft 17. Camming of the lever 8 to the left will permit the lever 7 to be depressed under the influence of the spring 15 25 which will allow the bell crank 15 to swing into latching relation with respect to the lever 7.

As the latch bar 3 is lowered to shift the bell crank 5, cam member 3' on the bar 3 20 moves this bar to the right by coaction with a shaft 46, to thereby disengage it from the bell crank after the bell crank is moved sufficiently to release the lever 7.

When the rollers 10, associated with the 25 lever 8, have moved out of the depressions 20, they ride on the thick portion of the thrust disc 11 and maintain the multiple disc clutch fully engaged until the opposite depressions are reached. During this period the action 30 of the thicker portions on the disc 11 will shift the lever 8 to the left, enabling resetting of the detent lever 7 to lock the lever 8 by rocking the latter slightly leftward to compress the spring 9. The pressure on the 35 disc 11 is maintained, however. Later on in the rotation of disc 11 the rollers again pass into the depressions 20 so that the end of the lever 8 abuts with the detent lever 7 which thereafter supports the rollers slightly out of 40 engagement with the base of the depressions 20, thus relieving pressure on the disc 11, and clutch discs 12. At this time, also, the latch member 21 engages one of the notches 22 to arrest the movement of the crank N.

45 The foregoing briefly sets forth the action of controlling 180 degree movements of the crank actuating shaft 17, and thereby controlling the movement of the discharge chute either from its discharging position to non-discharging position, or vice versa.

Skip operating control from power discharge mechanism

50 Referring now to Figure 8 and also Figures 3 to 7 of the drawings, it is notable that the object now to be accomplished is the operation of the clutch instrumentalities by which the hoisting means for the skip C are 55 thrown into action to raise the skip, through the medium of the power discharge mechanism hereinbefore set forth. With this in mind the description proceeds.

55 The pinion 16 carries on the opposite side 60 from the notched flanged portion a cam 26.

This cam has two functions: First, it is the actuating means for a push rod 27 operating the hand lever 51, which throws in the skip hoist clutch, and second, it actuates a crooked lever 28, see Figures 6 and 7, to move the 70 forked lever 29 to the right to swing the knock-out bar 3a out of the path of the bell crank release lever 5. The bar 3a operates in a manner similar to the latch bar 3, but this bar 3a is under the control of the skip. 75

Thus in the ordinary operation of the machine, in a full automatic cycle, it is contemplated that the cam 26 of the pinion 16 shall cause the rising movement of the skip C. Figure 6 shows the pinion 16 with the 80 cam 26; also Figures 7 and 8. It will be apparent, therefore, that at a predetermined time in the rotation of the gear 16 in the power discharge operation, as the chute is turned from the non-discharging to discharging position, the cam 26 will act on the roller 48 carried by the push rod 27 and hung on a horizontal arm 56 of the shaft 57, see Figure 8. In this manner, the cam 26 forces the push rod 27 rearward as seen in Figures 90 6 to 8, and since the push rod 27 is attached to a rigid arm 50 on the clutch lever rocker shaft 50a, by a yielding connection, seen best in Figures 9 and 10, as the spring means 49, the clutch mechanism for causing the operation of the skip C to rise will go into action.

It is desired, as previously stated, to incapacitate the skip, so far as its raising operation is concerned, to have any effect upon the power discharge mechanism except only in 100 the event that the power discharge chute happens to be in discharging position when the skip goes up.

With the foregoing in mind therefore, and referring to Figure 10, there are shown provisions such that the upward movement of the skip cannot affect the action of the power discharge mechanism to cause it to operate, and in this connection see also Figures 6 and 7. In Figure 10 there is illustrated at 30 a 110 roller abutment member supported by an arm fixed to the pivot axis 31 supporting the skip C. The said arm 30 is cooperative with an abutment arm 32 on a stub-shaft 33 which in turn carries a rocker arm 34, spring retracted in action, the rocker arm 34 being connected by a rod 35 with a bell crank lever 36.

The lever 36 is journaled on a stub shaft 36a projecting from the lower portion of the casing I and said lever 36 is furthermore connected by a rod 37 extending upwardly and attached to an arm 38 supported by a shaft 39 which is slightly above the shaft 41 carrying the batchmeter controlled lever 1. The connections just mentioned place under the control of the rising movement of the skip, the rocking of the shaft 39 and this shaft 39 carries an arm 40 supporting the short knock-out bar 3a which has been previously referred to as arranged to connect with the bell crank 130

release lever 5. Normally the knockout bar 3a is above the bell crank release lever 5 and capable of rocking the lever 5 to release the detent lever 7 and therefore release the 5 clutch engaging lever 8. This knockout bar 3a is normally arranged to actuate the lever 5 so as to make sure that on the upward movement of the skip if the discharge chute is at its discharging position, it will be returned 10 to its non-discharging position. Since, however, it is not desired to have the knockout bar 3a act upon the parts 5 and 7 in the above manner, if the discharge chute is already in its non-discharging position, the cam 26 will 15 under such a condition be so adjusted that it will act upon the lower crooked end of the crooked lever 28 and will have shifted said lever to the right, as seen in Figure 6, thereby causing the floating link 29 attached to said 20 lever 28 to abut with and swing to the right the knockout bar 3a into such a position that the bar even tho later swung downwardly by the normal operation of the parts supporting same, will be ineffective and will not in any 25 way disturb the adjustment of the discharge chute because of failure of the power discharge mechanism to act upon such chute.

Manual control to operate discharge chute

30 We have seen that the discharge chute may be caused to operate first by the batchmeter actuation of the lever 1 and downward movement of the latch bar 3; secondly, by the operation of the knockout bar 3a controlled 35 by the skip when the chute is in its discharging position as the skip moves upward. There is a third control of this discharge chute action which is manual and is dependent upon the movement of a foot pedal 43, seen in 40 Figure 5, and in Figure 1, which foot pedal is fixed with the shaft 41 of the upper portion of the casing I, said shaft 41 being the axis of the sleeve shaft 2 that carries the lever 1 and also the axis of the arm 42. 45 Obviously, if the foot pedal 43 is depressed, it will rock the shaft 41 and cause a third knockout bar 3b, seen best in Figure 3, to move downwardly and thereby trip the release lever 5 so as to release the clutch engaging lever 8 and permit the clutch devices 12 and 13 to go into action to effect a 180 degree movement of the shaft 17 and its arm N. The foot pedal action just described is therefore simple and may be performed at all 55 times except when the batchmeter has taken control, so to speak, of the power discharge mechanism.

Under the last condition, that is during the time period that the batchmeter is governing the action of the power discharge mechanism, the latch bar 3 is in the position of Figure 6, wherein the toe 44 of the latch bar is beneath the right hand end of the bell crank release lever 5. Obviously under 60 this condition, it is impossible for the foot

pedal to depress its knockout bar 3b to rock the lever 5 sufficiently to effect a release of the detent lever 7 so that the power discharge chute operating clutch is maintained inoperative by the foot pedal action as previously outlined. 70

Each of the parts 3, 3a and 3b has a cam 3' formed upon its inner edge arranged to slide against the shaft 46 to thereby upon downward movement of the particular part 75 having such cam, cause the part to be swung outwardly from a point above the right hand end of the crank lever 5, disengaging from said lever at the end of the operating stroke of the parts 3, 3a or 3b, and leaving the lever 5 and associated parts controlling the clutch lever 8 in a condition to be normalized by means previously described. 80

Manual control preventing automatic operation power discharge chute from batchmeter

In Figures 6, 7 and 13 and also in Figure 4, I show a hand lever 45 as carried outside the casing I and fixed to the shaft 46 previously described. The shaft 46 has a semi-circular cam 47 fixed thereto within the casing, see Figure 4 particularly, and by swinging the lever 45 in one direction the cam 47 acts on the latch bar 3 to shift this latch bar 90 rearward as seen in Figure 7 whereby it is ineffective to depress or rock the lever 5 and virtually incapacitate it so far as affecting the clutch lever 8 is concerned. Since the latch bar 3 establishes the control between the batchmeter and the clutch engaging lever 8, obviously when the parts are adjusted as in Figure 7 the batchmeter is powerless to trip the power discharge mechanism into action to operate the chute. Even under the conditions just stated, however, where the parts are as in Figures 7 and 13, the toe 44 of the latch bar 3 still remains in a position beneath the right hand end of the lever 5 and prevents a sufficient amount of downward movement of the right arm of the lever 5 to disengage the abutment portion 6 of the left arm of the lever from the detent lever 7. Later when the batchmeter performs its release operation at the end of the mixing period, the latch bar 3 will move down as in dotted lines in Figure 7 and render the power discharge mechanism controllable from the foot pedal 43. 100

The reason for the above cooperation of the parts is that never is it permissible to allow the foot pedal 43 to take control of the power discharge away from the batchmeter once the batchmeter control is established. But after the batchmeter has completed its control action at the end of a mixing period, it is sometimes desired that the discharge chute though turned over to discharge position be immediately restored to prevent discharge of the mixing drum. This can be 110 125 130

done readily, owing to the above interlocking of control, and of course, when the batch-meter is not hooked up by its control of the power discharge mechanism, the foot lever 43 is free at any time to take charge of the operation of the said discharge mechanism and to cause operation of the discharge chute as many times as may be desired. Each time the discharge chute would be operated 10 in the manner just mentioned, to swinging from non-discharging to discharging position, the upward movement of the skip C would be compelled unless some provision were made to prevent this which brings us 15 to the mechanism for the latter purpose, and for the general purpose of enabling a manual control of the upward movement of the skip at any time should it be desired.

Referring again to Figures 9, 10 and 11, 20 there has been described already the action of the rod 27 by which the short rocker member 50 resiliently connected to the rod 27 by spring 49, may be actuated from the cam 26. The rocker lever 50 is freely mounted upon 25 the shaft 50a alongside an auxiliary or complementary rocker lever 51a which directly carries the hand lever 51 previously mentioned. The lever structure 51, 51a is connected to throw the clutch yoke lever 51b of 30 a clutch and brake unit commonly used in machines of the type of this invention, and of which the brake member is designated 51c. The rocking of the hand lever 51 and its auxiliary member 51a causes a movement of 35 a rod 51d attached to a double crank lever 51e, see Figure 10, the rod 51f being also attached to said double crank lever 51e. The rod 51f is directly attached to a lever 51g of the clutch and brake unit previously mentioned, the action of which is known and 40 conventional.

With the parts just referred to in mind, the problem of this mechanism being described is merely to connect or disconnect 45 the push rod 27 operatively in relation to the clutch and brake unit and especially the clutch feature of the latter. To this end, there is employed a manual control device that is shown best in Figure 11 as comprising 50 a locking pin 52 normally spring pressed by a spring 53 and mounted upon the lower part of the lever structure 51, 51a. The pin 52 normally extends into the path of movement of the rocker lever 50 as effected 55 under the movement of the rod 27, see Figure 9, and when so extending or projected, obviously the lever structure 51, 51a will be rocked by the movement of the part 50. This 60 will communicate to the clutch means a clutching operation initiated from the rod 27, the latter in turn operated at a certain time in the operation of the power discharge mechanism including the parts 16 and 26. 65 Specifically this operation takes place when

the discharge chute moves from non-discharging position to the discharging position so that the operation of raising the skip C for charging the mixer is compelled to overlap the operation of emptying the mixing drum of its contents by means of the discharge chute H.

Under the foregoing conditions the action of the skip C to move upwardly is part of a normal automatic cycle of the machine but it may be desired at times not to have the skip C rise to charge the mixing drum under the automatic control of the power discharge mechanism. The skip might not be loaded, or if loaded from a truck, the truck may be resting upon the skip at its rear wheels, or a similar condition present itself. To the end of cutting out the automatic action of the skip just mentioned, I may utilize as seen best in Figures 9 and 11, a manual lever 54 equipped with a cam 54a at its hub portion arranged to engage a side of the lever 51a, said lever 54 being fixed by a set screw to the lock pin 53. Thus as the lever 54 is turned, its cam 54a will act to retract the pin 52 from a position in the path of movement of the rocker lever 50 and thereupon if the power discharge mechanism operates to shift the push rod 27 there will be no throwing in of the skip hoist clutch by the clutch yoke lever 51b, and no upward movement of the skip will automatically ensue.

The manual lever 54 is formed with a cam extension 54c which by a sufficient movement of the lever 54 may be turned to engage the fixed bracket structure 54d of the machine and by the impinging action of the cam 54e the lever structure 51, 51a is positively held in a position with the skip hoist clutch disengaged and the skip bracket 51c previously referred to rendered operative so that the skip will be positively held in any desired elevated position and locked from being lowered until these manually controlled parts are released. It should be noted at this time that the pin 52 would be held out of engagement with the rocker lever 50, and therefore, incapacitated for any action from the power discharge mechanism.

The reason for providing the spring 49 is to be specially noted, because by its use, if the operator should suddenly observe that the skip C while under automatic control of the power discharge, should not be elevated to charge the mixer, he may quickly grasp the hand lever 51 and by holding some tightly against rocking under the influence of the push rod 27 prevent the skip hoist clutch from going into action and thereby interrupt the automatic cycle of operation to this extent, the spring 49 in these circumstances merely becoming compressed and the rod 27 sliding through its bearing in the rocker lever 50.

Skip rising action non-automatic

There is provided according to Figure 12 a construction in which the upward movement of the skip of the machine is not a part 5 of the automatic cycle of operation as hereinbefore set forth. That is to say, the clutch mechanism including the part 51b known as the skip hoist clutch, is normally not susceptible of being actuated automatically from 10 the power discharge and must be rendered operative under the control of said discharge by a manual intervention.

To this end, according to Figure 12, the locking pin 52 previously set forth, is normally held out of engagement with respect 15 to the path of movement of the rocker lever 50' by means of the spring 53'. Thus the power discharge may operate as much as it will, and no action is compelled on the part 20 of the skip hoist clutch means. But there is provided a manual lever 58, preferably foot operated which the operator of the machine may depress any time he wishes and by so doing, the pin 52' will be forced into the path 25 of movement of the rocker lever 50' and the power for causing the skip hoist clutch to be thrown in, will be now transmitted to the lever structure which comprises the parts 51a and 51 which are like those previously 30 described.

In the construction of Figure 12, the lever 54' is adapted to act in an obvious manner as a means to positively lock the foot lever 58 from being depressed and when the lever 35 54' is so adjusted, it is not possible for the skip C to be raised by the action of the power discharge, and through any depression of the lever 58.

In all constructions of my machine as above 40 proposed, it is evident that the operation of the skip C is always under the control of the lever 51, this being a highly desirable feature because of possibilities arising that the skip C should not be raised due to the up- 45 springing of a peculiar condition occurring in the practical use of the machine.

In accordance with this invention, it is contemplated to supply water to the mixing drum from a suitable tank or source of supply. From the cycle of operation of the machine, furthermore, the water supply is turned on to cause water to pass into the mixing drum as an incident to the upward movement 50 of the skip. The water is caused to pass to the drum until the amount required is therein, after which the valve is turned off when the skip descends.

Having thus described my invention, what 60 I claim as new and desire to secure by Letters Patent of the United States, is:—

1. In a paving machine, in combination, a concrete mixer, charging means therefor, discharging means therefor, power operated means for actuating said charging and dis-

charging means, a timing device for the control of the operation of the discharging means, an operating connection intermediate the timing device and the power operated means to initiate the operation of the power operated means, means whereby said connection is normally inactive, and means manually to render said connection operative.

2. In a paving machine, a concrete mixer, a charging device therefor, means to cause discharging of the mixer, a batchmeter for timing the action of the discharging device by causing it to act after a predetermined mixing period, power mechanism under the control of the batchmeter for directly operating the discharging device, a connection operated by said power mechanism for initiating the operation of the charging device and normally inoperative, and means manually to render said last mentioned connection active.

3. In a concrete paving machine, a concrete mixer, a charging device therefor, a discharging device therefor, a single power unit, connections between the power unit and the discharging and charging devices for the actuation of the latter, and separate means associated with the power unit and the charging means for setting said power unit into action, said means being initiated into operation by the charging means.

4. In a concrete paving machine, a concrete mixer, a charging device therefor, a discharging device therefor, a power unit, means operatively associated with said charging device to be operated thereby for automatically setting said power unit into action, the power unit including a driving member, connections from the driving member to the discharging device and to the charging device, and means for resetting the parts of the power unit for a subsequent operation when said power unit is set into action to cause operations of the charging device and discharging device.

5. In a paving machine, in combination, a concrete mixer, a discharge device therefor, a charging device therefor, a power unit comprising a driving member, an operating connection for initiating charging action of the charging device leading from said driving member and normally inactive with respect to the operation of the driving member, means manually to render said connection active to initiate operation of the charging device by the driving member, and means for setting the power unit into action.

6. In a paving machine, in combination, a concrete mixer, a discharge device therefor, a charging device therefor, a power unit comprising a driving member, a batchmeter, means between the batchmeter and said driving member for setting the latter into operation, a manual means separate from the batchmeter for setting the driving member into action and connections leading from the

driving member to the discharging device for the operation of the latter.

7. In a paving machine, in combination, a concrete mixer, a discharge device therefor, a charging device therefor, a power unit comprising a driving member, a batchmeter, means between the batchmeter and said driving member for setting the latter into operation; a manual means separate from the batchmeter for setting the driving member into action and connections leading from the driving member to the discharging device for the operation of the latter, and means whereby the action of the driving member may be caused to initiate the operation of the charging device and normally inactive, together with means manually to render the said last mentioned means active.

8. In a paving machine, in combination, a concrete mixer, a discharging device therefor, a charging device therefor, a power driving member, an operating connection between the power driving member and the charging device for causing operation of the discharging device under a certain condition, and means to prevent operation of the discharging device by the charging device under other conditions.

9. In a paving machine, in combination, a concrete mixer, a discharging device therefor, a charging device therefor, a power driving member, an operating connection between the power driving member and the charging device for causing operation of the discharging device under a certain condition, means to prevent operation of the discharging device by the charging device under other conditions and a batchmeter timing device cooperating with the power driving member to cause operation of the discharging device after a predetermined time period.

10. In a paving machine, in combination, a concrete mixer, a discharging device therefor, a charging device therefor, a single power driving unit, means intermediate the charging device and said power driving unit to cause the discharging device to be operated to assume non-discharging position when the charging device is operated to charge the mixer, and means to prevent operation of the discharging device by the charging device when said discharging device is in non-discharging position.

11. In a paving machine, in combination, a concrete mixer, a discharging device therefor, a charging device therefor, a power driving unit, means intermediate the charging device and said power driving unit to cause the power unit to operate the discharging device causing the same to assume non-discharging position when the charging device is operated to charge the mixer, means whereby the charging device is rendered normally inoperative relation to the operation of the power driving unit and therefore incapable

of operating the latter, and means manually to render said charging device operative relatively to the power driving unit.

12. In a paving machine, in combination, a concrete mixer, a discharging device therefor, a charging device therefor, a power driving unit, means to operate the discharge chute from said unit, means to operate the charging device from said unit, means operable from the charging device to set the power drive unit into operation for the purpose of actuating the discharging device, an instrumentality for preventing the charging device from causing the power unit to operate the discharging device when said discharging device is in non-discharging position.

13. In a paving machine, in combination, a concrete mixer, a discharging device therefor, a charging device therefor, a power driving unit, connections from the power driving unit for the actuation of the discharging device and for the actuation of the charging device, an instrumentality cooperating between the charging device and said power driving unit for causing the unit to operate the discharging device during charging action of the charging device, and another instrumentality operatively arranged between the power unit and the charging device for preventing the charging device from causing an operation of the discharging device when said discharging device is in non-discharging position.

14. In a paving machine, in combination, a concrete mixer, a discharging device therefor, a charging device therefor, a power driving unit, a connection between the unit and the discharging device for the operation of the discharging device, a connection between the charging device and the power driving unit rendered operable when the charging device is doing its charging work to cause the discharging device to move from a discharging position into a non-discharging position, and means manually to render the condition between the power driving unit and the charging device active so that the operation of the power driving unit may initiate a charging movement of the charging device.

15. In a paving machine, in combination, a concrete mixer, a discharging device therefor, a charging device therefor, a single power driving unit for operating the discharge device and the charging device, and a batchmeter controlled by the charging device and in turn controlling the operation of the power driving unit.

16. In a paving machine, in combination, a concrete mixer, a discharging device therefor, a charging device therefor, a power driving unit comprising a clutch controlling device for starting the driving action of the unit, connections from the power driving unit to the discharging device and the charging device for the operation of these parts, a detent lever for normally maintaining the

clutch controlling device so that the power driving unit is inactive and a batchmeter connected with the power driving unit to release said detent and render the unit active.

5 17. In a paving machine, in combination, a concrete mixer, a discharging device therefor, a charging device therefor, a power driving unit comprising a clutch controlling device for starting the driving action of the 10 unit, connections from the power driving unit to the discharging device and the charging device for the operation of these parts, a detent lever for normally maintaining the clutch controlling device so that the power 15 driving unit is inactive and a batchmeter connected with the power driving unit to release said detent and render the unit active, and means controlled by the charging device for releasing the said detent and thus rendering the power unit active. 20

18. In a paving machine, in combination, a concrete mixer, a discharging device therefor, a charging device therefor, a power driving unit comprising a clutch controlling device for starting the driving action of the 25 unit, connections from the power driving unit to the discharging device and the charging device for the operation of these parts, a detent lever for normally maintaining the 30 clutch controlling device so that the power driving unit is inactive and a batchmeter connected with the power driving unit to release said detent and render the unit active, and means controlled by the charging device for releasing the said detent and thus rendering the power unit active, the power unit comprising a part cooperating with the last 35 mentioned means so as to prevent at certain times the charging unit from releasing said 40 detent and causing the power driving unit to become active.

19. In a paving machine, in combination, a concrete mixer, a discharging device therefor, a charging device therefor, a power 45 driving unit comprising a clutch controlling device for starting the driving action of the unit, connections from the power driving unit to the discharging device and the charging device for the operation of these parts, a detent lever for normally maintaining the clutch controlling device so that the power 50 driving unit is inactive and a batchmeter connected with the power driving unit to release said detent and render the unit active, means controlled by the charging device for releasing the said detent and thus rendering the power unit active, and a manual device operable to directly release the detent and render the power driving unit 55 active. 60

20. In a paving machine, in combination, a concrete mixer, a discharging device therefor, a charging device therefor, a power driving unit comprising a clutch controlling device for starting the driving action of the 65

unit, connections from the power driving unit to the discharging device and the charging device for the operation of these parts, a detent lever for normally maintaining the clutch controlling device so that the power 70 driving unit is inactive and a batchmeter connected with the power driving unit to release said detent and render the unit active, means controlled by the charging device for releasing the said detent and thus rendering the power unit active, and a manual device operable to directly release the detent and render the power driving unit active, and means whereby the last mentioned manual means is locked against rendering the power 75 unit active when the batchmeter has been set so as to control its means for releasing said detent. 80

21. In a paving machine, in combination, a concrete mixer, a discharging device therefor, a charging device therefor, a power unit comprising a clutch for connecting a constantly driving part therewith so as to drive the power unit, a detent for normally maintaining said clutch disengaged, a batchmeter, a connection from the batchmeter including a latch bar for releasing the detent and causing the clutch to become engaged to set the power unit into operation, and means operated from the power unit when it is set into 90 action adapted to cause operation of the charging device. 95

22. In a paving machine, in combination, a concrete mixer, a discharging device therefor, a charging device therefor, a power unit comprising a clutch for connecting a constantly driving part therewith so as to drive the power unit, a detent for normally maintaining said clutch disengaged, a batchmeter, a connection from the batchmeter including a latch bar for releasing the detent and causing the clutch to become engaged to set the power unit into operation, and means operated from the power unit when it is set into 100 action adapted to cause operation of the charging device, a manual device associated with the power unit, instrumentalities whereby the manual device on operation may also release the detent coacting with the clutch, and connecting means between the charging device including an instrumentality for causing release of said detent at a certain time in the operation of the charging device. 105 110 115

23. In a paving machine, in combination, a concrete mixer, a discharging device therefor, a charging device therefor, a power unit comprising a clutch for connecting a constantly driving part therewith so as to drive the power unit, a detent for normally maintaining said clutch disengaged, a batchmeter, a connection from the batchmeter including a latch bar for releasing the detent and causing the clutch to become engaged to set the power unit into operation, and means operated from the power unit when it is set into 120 action adapt- 125 130

ed to cause operation of the charging device, a manual device associated with the power unit, instrumentalities whereby the manual device on operation may also release the 5 detent coating with the clutch, and connecting means between the charging device including an instrumentality for causing release of said detent at a certain time in the operation of the charging device, means whereby the operating 10 instrumentality between the charging device and the said detent cannot be actuated to cause release of the detent when the batchmeter contrivances for the same purpose are set to control the detent, together with other 15 means which prevents the manual device from operating the detent under the same condition of control of the detent when the batchmeter is set.

24. In a concrete paving machine, comprising a concrete mixer, a charging device and a discharging device together with a batchmeter for controlling the operation of the discharging device, a power driving unit comprising a normally constantly rotating 25 part, driving gearing, a clutch for connecting said constantly driven part to the gearing, a clutch lever, a spring tending to move said clutch lever to engage the clutch, a detent for normally holding the clutch disengaged, and a connection between the batchmeter and 30 said detent for releasing the latter at a predetermined time.

25. In a concrete paving machine, comprising a concrete mixer, a charging device and a discharging device together with a batchmeter for controlling the operation of the discharging device, a power driving unit comprising a normally constantly rotating part, driving gearing, a clutch for connecting 35 said constantly driven part to the gearing, a clutch lever, a spring tending to move said clutch lever to engage the clutch, a detent for normally holding the clutch disengaged, and a connection between the batchmeter and 40 said detent for releasing the latter at a predetermined time, a manual device on the power unit, a knockout member operable thereby to release the detent, and means such that the knockout member is inactive to release the 45 detent when the batchmeter has been set and is controlling the detent according to a fixed period of time of mixing.

26. In a concrete paving machine, comprising a concrete mixer, a charging device and a discharging device together with a batchmeter for controlling the operation of the discharging device, a power driving unit comprising a normally constantly rotating part, driving gearing, a clutch for connecting 55 said constantly driven part to the gearing, a clutch lever, a spring tending to move said clutch lever to engage the clutch, a detent for normally holding the clutch disengaged, and a connection between the batchmeter and 60 said detent for releasing the latter at a predetermined time.

terminated time, a manual device on the power unit, a knockout member operable thereby to release the detent, and means such that the knockout member is inactive to release the 70 detent when the batchmeter has been set and is controlling the detent according to a fixed period of time of mixing, a separate means on the power unit operably connected with the charging device to be actuated thereby at a predetermined time, a knockout member carried by said separate means for releasing the detent from the clutch lever, and means to render the last mentioned knockout member inactive when the batchmeter is set 75 as above described.

27. In a concrete paving machine, comprising a concrete mixer, a charging device and a discharging device together with a batchmeter for controlling the operation of the discharging device, a power driving unit comprising a normally constantly rotating part, driving gearing, a clutch for connecting 80 said constantly driven part to the gearing, a clutch lever, a spring tending to move said clutch lever to engage the clutch, a detent for normally holding the clutch disengaged, and a connection between the batchmeter and 85 said detent for releasing the latter at a predetermined time, a manual device on the power unit, a knockout member operable thereby to release the detent, and means such that the knockout member is inactive to release the detent when the batchmeter has been set and is controlling the detent according to a fixed period of time of mixing, a separate means on the power unit operably connected with the charging device to be actuated thereby at a predetermined time, a knockout member carried by said separate 90 means for releasing the detent from the clutch lever, and means to render the last mentioned knockout member inactive when the batchmeter is set as above described, and still other means for manually incapacitating the batchmeter connection to the power unit to prevent it from releasing the detent so as to thereby prevent the discharge device from being operated by the action of the batchmeter.

28. In a paving machine, in combination, a concrete mixer, a discharging device therefor, a charging device therefor, a hoisting lever for the operation of the charging device, a power driving unit, connections between the power driving unit and the charging device, a hoisting lever normally inoperative, a manual operating device, and means actuated by said manual device to render said connections operative upon the skip hoisting lever.

29. In a paving machine, in combination, a concrete mixer, a discharging device therefor, a charging device therefor, a hoisting lever for the operation of the charging device, a power driving unit, connections be- 130

- 5 between the power driving unit and the charging device, a hoisting lever normally inoperative, a manual operating device, and means actuated by said manual device to render said connections operative upon the skip hoisting lever, and a second manual device cooperative with the first manual device to prevent the operation of the latter for rendering said connections active.
- 10 30. A mixer, means whereby to discharge the mixer and means for charging the mixer, the power discharge unit cooperative with the discharge means aforesaid, automatic control mechanism for causing operation of the discharge means, manual means for causing action of the discharge means to move it into and out of operative positions for discharging at will and as many times as desired, and an instrumentality for preventing the action of the manual means aforesaid when the discharging means is under the control of the automatic means.
- 15 31. A mixer, means whereby to discharge the mixer and means for charging the mixer, the power discharge unit cooperative with the discharge means aforesaid, automatic control mechanism for causing operation of the discharge means, manual means for causing action of the discharge means to move it into and out of operative positions for discharging at will and as many times as desired, and an instrumentality for preventing the action of the manual means aforesaid when the discharging means is under the control of the automatic means, the said automatic means including a signal to indicate the time of completion of a lapsed period of mixing.
- 20 32. A mixer, means whereby to discharge the mixer and means for charging the mixer, the power discharge unit cooperative with the discharge means aforesaid, automatic control mechanism for causing operation of the discharge means, manual means for causing action of the discharge means to move it into and out of operative positions for discharging at will and as many times as desired, and an instrumentality for preventing the action of the manual means aforesaid when the discharging means is under the control of the automatic means, the said automatic means including a signal to indicate the time of completion of a lapsed period of mixing, and a manual device for preventing the discharging means from becoming operative when the signal is operated.
- 25 33. In a machine of the class described, in combination, a mixer comprising instrumentalities for causing discharge action thereof and means for charging the same, a timing device under the control of the charging means for timing the period of mixing operation, a power discharge unit associated with the timing device and adapted to be placed in operation thereby for causing ac-
- tion of the means for discharging the mixer in an automatic manner, a manual control so connected with the said power discharge unit that after the timing device has been actuated, the power discharge unit may be controlled to discharge a portion or all of the batch from the mixer.
- 30 34. In a paving machine, in combination, a concrete mixer, a discharge device therefor, a charging device therefor, a single power driving unit, means for automatically, and means for independently manually causing actuation of the power unit, means connecting the said unit to operate the discharging device, connections leading from the unit for the operation of the charging device, and manual means for rendering the power unit inoperative with respect to the automatic actuating means to permit manual control at will thereof.
- 35 In testimony whereof I affix my signature.
